UNITED STATES PATENT OFFICE.

CHARLES W. SHARTLE, OF MIDDLETOWN, OHIO.

BEATER ROLL OF PAPER-MILL MACHINERY OR THE LIKE.

Application filed June 18, 1923. Serial No. 646,014.

To all whom it may concern:

Be it known that I, CHARLES W. SHARTLE, a citizen of the United States, residing at Middletown, in the county of Butler and 5 State of Ohio, have invented certain new and useful Improvements in Beater Rolls of Paper-Mill Machinery or the like, of which the following is a specification, reference being had therein to the accompanying 10 drawings.

This invention relates to improvements in beater rolls of paper mill machinery, having particular reference to an improved method of mounting the fly bars on the beater 15 rolls.

As herein shown and described, the means employed to effect the improvements of the invention consist in various forms of interlocking devices adapted to be shrunk onto 20 the beater roll heads in engagement with the fly bars whereby to interlock the same with the heads. The arrangement provides for mounting the fly bars singly, or in sets, so that each bar or set of bars can be mounted, 25 adjusted and replaced independently of the other bars.

The principle of the invention lends itself readily to suitable modifications of construction with reference to the shape or 30 character of the interlocking devices. In the various practicable forms in which the invention can be applied the arrangement tends toward simplified construction, with the further advantages gained in maintenance by the independent mounting of the 35 fly bars.

In the accompanying drawings:

Fig. 1 is a side elevation of a beater roll of the usual construction;

Fig. 2 is an end view of a beater roll illustrating the improved method of mounting the fly bars in one form of arrangement.

Fig. 3 is a detail view in longitudinal section of the construction shown in Fig. 2.

Fig. 4 is a detail end view illustrating a modification of construction shown in Fig. 2.

Fig. 5 is a detail end view illustrating a further modification of the construction 50 shown in Fig. 2.

As shown in Figs. 1 and 2 the usual features of construction of beater rolls consist of the shaft —1, ends or heads —2, head retaining flange —3, intermediate supports 55 —4, fly bars —5 and wood filling —6, the means shown for interlocking the fly bars

with the beater roll heads being features of the present invention.

In the construction shown in Figs. 2 and 3, each fly bar is mounted independently, 60 the means employed for mounting the bars consisting of a series of lugs —7, arranged circumferentially on the outer faces of the beater roll heads —2, the lugs, as shown, being cast integrally with the heads, and 65 defined by depressions —8, in the metal, the over-all face surface of the heads, being substantially flush; slots —9 formed in the outer edge of heads —2, intersecting the lugs —7, and adapted to receive the ends of the 70 fly bars —5; interlocking bands —10 adapted to be shrunk over lugs —7 and to engage the ends of the fly bars by means of slots —11 formed therein, whereby each fly bar is independently secured in the opposite 75 heads of the beater roll, being supported between ends by intermediate members —4, and is adapted to be mounted, adjusted and replaced independently of the other bars.

The construction illustrated in Fig. 4 is 80 essentially the same in principle as that shown in Figs. 2 and 3. As shown the lugs —12 and shrink bands —13 are triangular-shaped, each lug and band being adapted to engage two fly bars. The advantage in this 85 consists in the fewer parts required, and in quicker mounting of the fly bars on the beater roll by arranging them in sets.

In Fig. 5 a modified construction is shown which is different in form but not essentially different in principle from that shown in Figs. 2 and 4. As shown the modified construction consists in depressions —14, 90 formed in the outer face of the beater roll heads —2, each of the depressions being arranged to intersect two of the head slots —9, and to be aligned with slots —11, of opposite fly bars —5; the interlocking members —15, which are shaped to fit depressions —14, being shrunk into the depressions 95 to firmly interlock the fly bars with the beater roll heads.

From the drawings and the foregoing detailed description the underlying principle of mounting the fly bars on the beater roll 105 heads by means of interlocking devices of any suitable shape shrunk on lugs or in depressions formed on the beater roll heads, and engaging the fly bars, singly or in sets, in a manner which serves to interlock the 110 same with the heads, will be readily understood.

Having described my invention, I claim:

1. In a beater roll the combination, including a beater roll head, a lug on the face of the head and a peripheral slot in the head intersecting said lug, a fly bar having an end supported in said slot, and a band shrunk over said lug engaging the end of the fly bar and interlocking the same with the head. 25
2. In a beater roll the combination, including a beater roll head, a lug on the face of the head and a plurality of peripheral slots in the head intersecting said lug, a fly bar supported in each slot, and a band shrunk over the lug engaging the fly bar in each slot and interlocking the same with the head. 30
3. In a beater roll the combination, including a beater roll head, a depression formed in the face of the head, a peripheral slot in the head intersecting said depression, a fly bar having an end supported in said slot, and a member adapted to be shrunk into said depression whereby to engage the fly bar and interlock the same with said head. 35
4. The herein described method of mounting beater roll fly bars consisting in forming a lug in the outer face of a beater roll head and a peripheral slot in the head to intersect the lug, in entering the end of a fly bar in said slot, and in shrinking a band over the lug in engagement with the fly bar. 40
5. The herein described method of mounting beater roll fly bars consisting in forming a lug in the outer face of a beater roll head and a plurality of peripheral slots in the head intersecting the lug, in entering the end of a fly bar in each slot and shrinking a band over the lug in engagement with the fly bars whereby a plurality of fly bars will be interlocked with the beater roll head in a single mounting.

In testimony whereof I affix my signature.

CHARLES W. SHARTLE.
